(57) **CLAIM**

The ornamental design for a weld cleaning device, as shown and described.

DESCRIPTION

FIG. 1 is front view of the weld cleaning device of the present design, as shown in a horizontal configuration;

FIG. 2 is a left side view of the weld cleaning device of the design of FIG. 1, as shown in the horizontal configuration; FIG. 3 is rear view of the weld cleaning device of the design of FIG. 1, as shown in the horizontal configuration; FIG. 4 is a right side view of the weld cleaning device of the design of FIG. 1, as shown in the horizontal configuration; FIG. 5 is a bottom plan view of the weld cleaning device of the design of FIG. 1, as shown in the horizontal configuration;

FIG. 6 is a top plan view of the weld cleaning device of the design of FIG. 1, as shown in the horizontal configuration; FIG. 7 is a front, left perspective view of the weld cleaning device of the design of FIG. 1, as shown in the horizontal configuration;

FIG. 8 is a back, left perspective view of the weld cleaning device of the design of FIG. 1, as shown in the horizontal configuration;

FIG. 9 is a back, right perspective view of the weld cleaning device of the design of FIG. 1, as shown in the horizontal configuration;

FIG. 10 is a front, right perspective view of the weld cleaning device of the design of FIG. 1, as shown in the horizontal configuration;

FIG. 11 is a front view of the weld cleaning device of the design of FIG. 1, as shown in a vertical configuration;

FIG. 12 is a left side view of the weld cleaning device of the design of FIG. 1, as shown in the vertical configuration;

FIG. 13 is a right side view of the weld cleaning device of the design of FIG. 1, as shown in the vertical configuration; FIG. 14 is a bottom plan view of the weld cleaning device of the design of FIG. 1, as shown in the vertical configuration;

FIG. 15 is a top plan view of the weld cleaning device of the design of FIG. 1, as shown in the vertical configuration;

FIG. 16 is a front, left perspective view of the weld cleaning device of the design of FIG. 1, as shown in the vertical configuration;

FIG. 17 is a back, left perspective view of the weld cleaning device of the design of FIG. 1, as shown in the vertical configuration;

FIG. 18 is a back, right perspective view of the weld cleaning device of the design of FIG. 1, as shown in the vertical configuration; and,

(Continued)

FIG. 19 is a front, right perspective view of the weld cleaning device of the design of FIG. 1, as shown in the vertical configuration.

The battery pack and the brushes shown in broken lines in the drawing form no part of the claimed design for a weld cleaning device.

The horizontal and vertical configurations of the design for a weld cleaning device constitute a single design as the head of the weld cleaning device is rotatable into either configuration.
